WHEEL BALANCING SPINNER

George T. Hemmeter, Los Altos, Calif.

Application May 21, 1956, Serial No. 41,557

Term of patent 14 years

(Cl. D52—1)

FIG-1

FIG-2

FIG-3

Figure 1 is a perspective view of a wheel balancing spinner, the cover being in closed position, showing my new design.

Figure 2 is a side elevation thereof.

Figure 3 is a perspective view thereof taken directly opposite to Figure 1.

I claim:

The ornamental design for a wheel balancing spinner, as shown.
